TOILET TISSUE RACK

Charles J. Siemienkiewicz, Webster, Mass.

Application March 30, 1955, Serial No. 35,285

Term of patent 7 years

(Cl. D4—3)

Fig. 1

Fig. 2

Fig. 3

I claim:

The ornamental design for a toilet tissue rack as shown.
